(57) **CLAIM**

The ornamental design for a combined child's slipper and rattle, as shown and described.

DESCRIPTION

FIG. 1 is a rear perspective view of a combined child's slipper and rattle embodying my new design;

FIG. 2 is a front perspective view of a combined child's slipper and rattle embodying my new design;

FIG. 3 is a front view thereof;

FIG. 4 is a rear view thereof;

FIG. 5 is a side view thereof, the other side view being a mirror image thereof;

FIG. 6 is a top view thereof; and,

FIG. 7 is a bottom view thereof.

The broken line showing the outsole in FIGS. 3, 4, 5 and 7 is for illustrative purposes only and forms no part of the claimed design.

The partial rendering of the crosshatched pattern is for ease of illustration. It is understood that the pattern continues throughout the surfaces on which it is only partially shown.
